SWITCH

Herman C. Kalwitz, Chicago, Ill.

Application January 11, 1932. Serial No. 585,861

15 Claims. (Cl. 200—48)

This invention relates to high voltage switches in general and more particularly to disconnect switches such as are adapted to be immersed in an oil bath. In its more specific aspect the 5 switch of the present invention constitutes an improvement on the disconnect switches shown in Figs. 6 and 7 of my pending patent application Serial No. 479,624, filed September 4, 1930.

10 In my above referred to application I show a metal clad substation wherein all of the parts are immersed in oil. Each disconnect switch is mounted in an oil tank and so arranged that a grounded barrier is moved between the terminals as the switch is opened. This is a feature necessary for the safety of the operator when the operator inspects or repairs the switch. When the switch is closed the grounded barrier is located above the switch at a distance determined by the insulation requirements. When the switch is opened the barrier moves downward between the contacts. Since compactness is one of the prime virtues of the metal clad switch gear it is apparent 25 that the switch housing or casing cannot be made so large as to encompass the barrier. The casing is therefore provided with an extension into which the barrier protrudes when the switch is closed and from which it is projected when the 30 switch is open. This extension increases the cost of the switch. It is an object of the present invention to eliminate the need for this extension. I propose to accomplish this end by making the barrier as a unit separate from 35 the switch proper and adapted to be inserted into the switch casing when the switch is open and removed therefrom prior to closure of the switch.

40 One of the reasons for interposing a grounded barrier between the two switch terminals is that it permits the safe inspection and repair of either one of the terminals while the other terminal is at its normal line voltage. The 45 distance between each terminal and the grounded barrier must therefore be such as to afford adequate insulation between the live terminal and ground. If the arrangement is such that the draining of the oil surrounding one terminal necessarily results in or requires the 50 draining of the oil surrounding the other terminal then the minimum allowable distance between the terminal and the grounded barrier must be figured on the basis of air as the insulating medium. I propose to make the ar-

rangements such that the barrier forms a liquid tight seal with the bottom and sides of the switch casing thus dividing the casing into two parts either one of which may be drained of its oil while leaving the other full of oil. By 60 this arrangement the oil may be drained from the side of the switch that is to be inspected or repaired and which is therefore at ground potential, while the other terminal, which may be at the line potential, is immersed in oil. 65 The spacing requirement between the live terminal and the grounded barrier is thus reduced, thereby reducing the overall size of a switch for a given voltage system.

The top of the switch casing is provided with 70 an opening through which the barrier may be inserted. A closure is provided for the opening, said closure being interlocked with the switch to prevent opening of the closure when the switch is closed. If desired the interlock 75 may be arranged to prevent reclosing of the switch when the closure is in its open position. This however is generally not necessary. The barrier is adapted to be inserted into position when the closure is open and is itself provided 80 with an arrangement for completely closing the barrier receiving opening in the casing.

The barrier comprises, preferably, a metallic plate provided with means for making good electrical contact with the sides of the casing, 85 which is grounded, thus assuring a grounding of the barrier. Various arrangements may be provided for making a liquid tight seal between the barrier and the casing. A simple arrangement consists merely of a rubber tube, 90 similar to an inner tube of a pneumatic tire, placed around the barrier and adapted to be inflated after the barrier has been inserted into the switch casing. Upon inflation of the tube 95 it is expanded into firm contact with the adjacent walls of the casing to form a liquid tight seal. As an alternative a solid rubber or leather rim may be used, the rim being made of a somewhat wedge shape to form a liquid tight seal as the barrier is inserted into place. 100

The attainment of the above and further objects of the present invention will be apparent from the following specification taken in conjunction with the accompanying drawings forming a part thereof. 105

In the drawings:

Figure 1 is a fragmentary transverse sectional view through a switch embodying the principals of my invention;

Figure 2 is a fragmentary top view thereof with the cover removed;

Figure 3 is a view similar to Figure 1 and showing the switch in its open position with the 5 separating barrier inserted in place;

Figure 4 is a sectional view taken along the line 4—4 of Figure 3 and looking in the direction of the arrows; and

Figure 5 is a front view of the removable 10 barrier.

The switch of the present invention is particularly adapted for use in an oil filled bus switching station of the type disclosed in my pending application, Serial No. 479,624, filed September 15, 1930, the present switch corresponding to the switch shown in Figures 6 and 7 of that application. The switch is mounted in an oil casing 1 which also constitutes a terminal box and which is provided with bottom, side, end and 20 top walls comprising an oil tight box. In switches that are adapted for use on medium high voltage systems the top is made in two parts, separately removable to permit inspection or repair of the switch within. In switches that 25 are designed for use on higher voltages the top is provided with a plurality of covers corresponding to man-hole covers for accomplishing this same purpose. It is to be noted that the disconnect switches used on very high voltage systems 30 are frequently so large that a man can enter into the switch casing through the cover.

The switch proper which is mounted within the casing 1 may be of any preferred construction and is here shown as an ordinary knife 35 switch comprising a terminal or contact 2 mounted on an insulator 3 and having a blade 4 pivoted thereon and adapted to be received between a pair of jaws of a terminal clip or contact 5 which is mounted upon an insulator 6. 40 The switch is adapted to be operated by means of a rotatable shaft 7 on which is keyed a crank 8, and a connecting rod 9 of suitable insulating material. A conductor 10 which extends the circuit to the terminal clip 5 of the disconnect switch is brought into the casing 1 through a bushing 12 which provides suitable insulation between the conductor and the end wall of the casing and also provides an oil tight seal at the conductor entrance. The conductor 14 which 45 extends the circuit to the terminal clip 2 of the disconnect switch is extended into the switch casing in a similar manner.

The casing 1 is grounded and is provided with a terminal clip 17 for receiving the free end of 50 the blade 4 when the blade is moved to its normal switch open position, thereby grounding the terminal clip 2 and the line conductor 14.

The top of the switch casing is provided with an opening 20 which extends for the full width 60 of the casing and is defined by a pair of oppositely facing flange members 21—21. The opening 20 is provided with a cover 22, hinged at 23 and adapted to be swung over the members 21—21 and form a closure for the opening 20. 65 An interlock is provided for preventing opening of the cover 22 when the disconnect switch is in its closed position. This interlock comprises a slidable rod 24 carried on suitable brackets on the underside of the cover 1 and adapted to enter an opening in a depending member 25 secured to the cover 22. When the switch is in its closed position the rod 24 engages the opening in the member 25 and prevents opening of the cover 22. When the switch is moved to its 70 open position the blade engages a projection 27

on the rod 24 and moves the rod out of engagement with the member 25. When the switch blade is again moved to its closed position it engages a member 28 on the rod 24 and thus moves the rod to its locking position. If the switch is moved to its closed position before the opening 20 has been closed it becomes impossible to thereafter swing the cover to its closed position, whereby the operator is apprised of this fact. If an attempt is made to close the switch with the cover 22 partly closed the rod 24 will abut against the member 25 and being thereby held against further movement it holds the blade against closure, thereby apprising the operator of the fact that the cover is not correctly closed. 80 85 90

The switch casing 1 is adapted to receive a barrier through the opening 20 when the blade is in its open position. For this purpose a channel guideway is provided along the side walls adjacent the opening and along the bottom wall. 95 This channel guideway comprises two angle iron members 30—30 secured to each side wall in spaced relation and extending downwardly from the opening 20 on the inner side of said wall. A similar pair of angle iron members 31—31 are 100 secured to the bottom wall of the casing 1.

A barrier, such as is illustrated in Figure 5, is provided for the purpose of dividing the switch housing into two separate sections. The barrier is separate from the switch and is adapted to be 105 inserted therein when the switch has been operated to its open position. The barrier comprises a metallic plate 35 of a generally rectangular cross section and provided with a tube of rubber or the like along its outer periphery. The tube is 110 indicated at 36 and is of a construction substantially similar to that of the inner tube used in pneumatic automobile tires. A valve stem 37 communicates with the tube and is adapted to receive the end of an air pump or the like for 115 the purpose of inflating the tube 36. The valve 37 extends through an opening in a cover member 38 secured to the plate 35. Resilient metallic strips 40 are secured to one side of the plate 35 and along the periphery thereof. These strips 120 are adapted to engage the angle iron members 30—31 within the switch casing for grounding the plate 35 when the barrier is inserted into the casing.

When it is desired to inspect the disconnect 125 switch, or to repair the same, the circuit through the disconnect switch is opened at some point other than the switch and the switch blade is then swung to its open position. Thereafter the cover 22 is opened and the barrier shown in Figure 5 is inserted into the casing through the opening 20. At this time the tube 36 is deflated and the barrier fits not too tightly within the channel defined by the angle members 30—30 and 31—31. The cover 38 which is a part of the 135 barrier fits over the members 21—21 thereby closing the opening 20. To facilitate the handling of the barrier the cover 38 is provided with a pair of handles indicated at 41—41. Upon inflation of the tube the resulting expansion produces a liquid tight seal between the rubber tube and the wall of the switch casing. At this time the flexible metal strips 40 are forced into firm electrical contact with the angle members 30 by the pressure within the tube 36, thus producing 140 a good ground connection to the metal plate 35. It is now possible to drain the oil from either 145 half of the switch casing while maintaining the other half of the casing full of oil. Assume that the right hand half of the casing is drained of 150

its oil while the left hand half is maintained full of oil. This means that the contact 5 is still immersed in its oil bath and therefore there is suitable insulation between this contact and the walls of the housing and also between this contact and the grounded barrier plate 35, even though the terminal 5 is at its line potential. The other half of the casing may be at ground potential whereby an operator may safely work upon the part within that half of the casing.

Attention is called to the fact that it is not always necessary to drain the oil from one of the sections of the switch housing. It is frequently possible to inspect or repair various parts of the switch while the same are immersed in oil. This may be done with safety when the barrier is in position, even though the other terminal is at line potential. This is so because the plate 35 is grounded.

20 While I have herein shown my invention as applied to a switch wherein the blade is grounded when the switch is open it is of course to be understood that the invention is not limited to such an arrangement since the grounding contact 17 may be omitted where necessary. Under such circumstances the contact 2 may be alive at the time the switch blade is in its open position whereas the contact 5 may be at ground potential because of the establishment of a ground connection to the conductor 10 at some remote point. In such an arrangement either of the contacts may be at line potential and immersed in its insulating oil while the other contact is at ground potential and free of its insulating oil for inspection or repair purposes.

While I have herein shown one particular arrangement for obtaining a liquid tight seal or closure between the two halves of the switch housing it is to be understood that other means for obtaining this same result may be used. For instance, instead of resorting to inflation of the tube 36 for producing this seal the equivalent effect may be obtained by providing a rubber or leather rim around the plate 35 for producing a wedging action within the channel defined by the angle members 30-30 and 31-31. Likewise, other equivalent arrangements may be used.

In compliance with the requirements of the patent statutes I have herein shown and described a preferred embodiment of my invention. It is however to be understood that the invention is not limited to the precise arrangement herein disclosed, the same being merely illustrative of the principles of the invention. What I consider new and desire to secure by Letters Patent is:

1. A switch comprising a housing, a pair of terminals therein and a switch member movable into and out of bridging relation with the terminals, said housing having an opening extending transversely across the top between the two terminals, a closure for the opening, barrier receiving guideways along the inner sides of the housing at the opening for receiving a barrier between the terminals, and a barrier insertable into the housing through the top thereof and engaging said guideways, said barrier having a pneumatic tube along at least a portion of the periphery thereof adapted to be inflated to form a liquid tight seal between the barrier and the walls of the housing.

2. A switch comprising a housing, a pair of terminals therein and a switch member movable into and out of bridging relation with the ter-

minals, said housing having an opening extending transversely across the top between the two terminals, a closure for the opening, barrier receiving guideways along the inner sides of the housing at the opening for receiving a barrier between the terminals, and a barrier insertable into the housing through the top thereof and engaging said guideways, said barrier having a pneumatic tube along at least a portion of the periphery thereof adapted to be inflated to form a liquid tight seal between the barrier and the walls of the housing, said barrier including a closure at the top thereof adapted to form a closure for the top opening in the housing.

3. An oil switch including an oil containing casing, a pair of spaced switch terminals mounted therein, a switch blade movable into and out of bridging relation to the terminals, a barrier movable between the terminals when the blade is in its open position, said barrier dividing the casing into two parts and making a liquid tight seal with the walls of the casing to permit emptying of one part of the casing while maintaining the oil filled condition of the other part.

4. An oil switch including an oil casing, a pair of relatively movable contact making members adapted to be moved into and out of engagement, and a barrier movable between the contact making members and forming a liquid tight seal with the walls of the casing.

5. A disconnect switch comprising two terminals and means for establishing and disestablishing a connection between them, a housing for the members, said housing having an opening at the top thereof, and a grounded barrier removably inserted through the opening and extending between the terminals and including a closure for the opening.

6. A disconnect switch comprising two terminals and means for establishing and disestablishing a connection between them, a housing for said terminals adapted to contain liquid insulation, and a grounded metallic barrier movable into a position between the terminals and making a liquid tight seal with the walls of the housing and dividing the housing into two separate chambers.

7. A switch including a housing and within the same a grounded barrier comprising a plate having a pneumatic tube along a portion of its periphery and adapted to be inflated into intimate contact with the walls of the housing.

8. A switch including a housing and within the same a grounded barrier comprising a plate having a rubber lining member along a portion of its periphery and adapted to make intimate contact with said housing to form a liquid tight seal between the portions of the housing on opposite sides of the barrier.

9. A barrier for insertion into a switch housing to divide the same into two hydraulically separate compartments, said barrier comprising a metallic plate having a rubber lining member along the major portion of its periphery and strips of spring metal secured to the plate adjacent the edges thereof and adapted to make electrical contact with a switch housing to ground the plate when the barrier is inserted into a switch housing.

10. A switch including cooperating switch terminals, a housing for the terminals, said housing having an opening at the top thereof, a closure for the opening, and a grounding barrier carried by the closure and extending between the terminals.

the terminals, whereby the presence of the closure indicates the presence of the grounded barrier between the terminals.

11. A switch including cooperating switch terminals, a housing for the terminals, said housing having an opening at the top thereof, a closure for the opening, a grounded barrier carried by the closure and extending between the terminals, whereby the presence of the closure indicates the presence of the grounded barrier between the terminals, and means for preventing the full movement of the barrier into the housing when the switch is closed and preventing the closing of the switch when the barrier is in position.

12. A switch including a pair of switch terminals, a housing therefor, said housing having an opening at the top thereof, a closure for the opening, means for preventing opening of the closure when the switch is closed, a second closure for the opening adapted to be used when the first closure is in its open position, and means for preventing closing of the switch when the second closure is over said opening.

13. A switch including a pair of switch terminals, a housing therefor, said housing having an opening at the top thereof, a closure for the opening, means for preventing opening of the closure when the switch is closed, a second closure for the opening adapted to be used when

the first closure is in its open position, and means for preventing closing of the switch when the second closure is over said opening, said second closure including grounding means movable between the switch terminals.

80

14. A switch including a pair of switch terminals, a housing therefor, said housing having an opening at the top thereof, a closure for the opening, means for preventing opening of the closure when the switch is closed, a second closure for the opening adapted to be used when the first closure is in its open position, and means for preventing closing of the switch when the second closure is over said opening, the two named preventing means including a common actuating rod actuated by the switch.

85

15. A switch including a pair of switch terminals, means for bridging the terminals, a housing for the terminals, said housing having an opening, closure means for the opening, means for preventing opening of the closure means when the switch is closed, grounding means movable through the opening into position between the terminals when the switch is open and insulated from at least one of the terminals, and means for locking the switch against substantial switch closing movement when the grounding means is in position between the terminals.
